(57) **CLAIM**

The ornamental design for an operating device for hoisting machine as shown and described.

DESCRIPTION

FIG. 1 is a perspective view of an operating device for hoisting machine, showing my new design;

FIG. 2 is a front view thereof;

FIG. 3 is a rear view thereof;

FIG. 4 is a right side view thereof;

FIG. 5 is a left side view thereof;

FIG. 6 is a top plan view thereof; and,

FIG. 7 is a bottom plan view thereof.

The broken lines in the drawings are for the purpose of illustrating portions of the operating device for hoisting machine that form no part of the claimed design.
